Merchandise Kilgore

UNITED STATES PATENT OFFICE

EDWARD W. HAMANN, OF MINNEAPOLIS, MINNESOTA

DISPLAY RACK

Application filed July 6, 1931. Serial No. 548,306.

My invention relates to display racks and more especially to such a rack for holding goods in their original containers such as bottles, jars, cans, cartons and the like.

5 While the invention is intended for such general use it is especially well adapted and designed for holding and displaying bottles containing beverages. The object of the invention is the provision of a display rack that is of lightweight, simple construction and of relatively small cost to manufacture and that will individually hold bottles or other articles placed thereon in compact and attractive form.

13 To the above end, generally stated, the invention consists of the novel construction and arrangement of parts hereinafter described and defined in the claims.

In the accompanying drawing, which illustrates the invention, like characters indicate like parts throughout the several views.

Referring to the drawing:

Fig. 1 is a perspective view of the improved display rack with a number of bottles indicated thereon by means of broken lines;

Fig. 2 is a view partly in plan and partly in horizontal section taken on the line 2—2 of Fig. 1;

39 Fig. 3 is a fragmentary view with some parts sectioned on the line 3—3 of Fig. 1, on an enlarged scale; and

Fig. 4 is a fragmentary view with some parts sectioned on the line 4—4 of Fig. 2 and further illustrating a number of bottles by means of broken lines.

The entire rack, as shown, is formed from wire or rods and the body thereof includes nine upright members 5, circumferentially spaced equi-distances apart, a base ring 6, and top, lower and intermediate shelves 7. These shelves 7 are spaced equi-distances apart, the one above the other, and the lower shelf 7 is relatively close to the base ring 6. 45 Each shelf 7 is formed by an outer ring 8 and an inner ring 9 and which rings are concentric, radially spaced and rigidly connected by a plurality of radial tie members 10, the outer ends of which are closely positioned to 50 certain of the uprights 5. The outer rings

8 encircle the uprights 5 and are rigidly secured thereto.

Above each shelf 7 are nine compartments 11 for individually holding bottles X. The rings 9 also act as guards for holding the bottles in the compartments 11, as will presently appear. These compartments 11, for each shelf 7, are formed by a plurality of circumferentially spaced members 12 that are inwardly and upwardly inclined from the respective outer ring 8 and in converging relation. The lower ends of the members 12 are secured to the outer ring 8 close to the upright members 5 and their upper ends are rigidly connected to a rest ring 13 equi-distances apart. A guard ring 14 corresponding to the rings 9 is rigidly secured to and supported above the upper rest ring 13 by a plurality of short upwardly and outwardly diverging tie-members 15. The lower ends 70 of these tie-members 15 are rigidly secured to the upper rest ring 13 and their upper ends are rigidly secured to the ring 14.

A holder 16, for individually holding one of the bottles X above the rack and at the center thereof, is formed by a lower ring 17, an upper ring 18, upright members 19 and bottom members 20. The upper ring 18 is vertically spaced above the lower ring 17 and said rings rigidly connected by the upright members 19 which are circumferentially spaced therearound equi-distances apart. These upright members 19 extend downwardly and outwardly from the lower ring 17 in diverging relation and are rigidly secured to the upper ring 13 and support the holder 16 above said ring 13 and concentric therewith. The bottom members 20 are laterally spaced and rigidly secured to the lower ring 17.

A spring clip 21 is provided for holding a display card Y above the rack for advertising the goods thereon. This clip 21 is formed by coiling the intermediate portion of a single piece of wire the end portions of which extend downward and form a pair of legs 22 rigidly secured to the rings 17 and 18 at diametrically opposite points and support the clip 21 from said holder at the axis of the rack.

Three crossed brace rods 23, within the

rack, are rigidly connected at their lower ends to the base ring 6 and at their upper ends to the ring 8 of the top shelf 7. The brace rods 23 at their points of intersection are rigidly connected, as indicated at 24, and produce a structure that is very rigid.

The bottle X in each compartment 11 is supported on the shelf 7 and held in an inwardly inclined position in which the bottle 10 at its bottom rests on the outer ring 8 with its back engaging the inner ring 9 and with its neck resting on the ring 13, as indicated by broken lines in Fig. 4. Obviously, the ring 9 holds the bottle X from slipping inward on the ring 8 and two members 12 forming the sides of the respective compartment 11 hold the bottle X against lateral movement. The two uppermost rings 9 and the ring 14 are below the tops of the bottles X 15 on the shelves 7 and prevent persons handling the bottles X on each shelf 7 from tipping the same outward on said shelves. The bottles X on each shelf 7 are held in conical formation so that only the fronts thereof are exposed. It will thus be seen that when the rack is filled with bottles the same forms a shell that is symmetrical and has a pleasing and attractive appearance. The position of the bottles on the rack is such that they may be easily removed 20 and the goods sold direct from the rack. The formation of the rack permits the same to be placed in any desired position on the floor and has the same appearance on all sides.

What I claim is:

- 35 1. A display rack comprising a body having an annular lower shelf and an annular upper shelf, and means above each shelf for holding articles thereon in conical formation, the vertical spacing of the shelves being such
- 40 2. that the tops of the articles on the lower shelf extend within and above the upper shelf, said body being further provided with a holder for holding one of the articles at the apex of the upper formation.
- 45 3. A display rack comprising a plurality of circumferentially spaced upright members, an annular shelf connecting the upright members and comprising inner and outer rings and tie-members connecting said rings and
- 50 4. holding the same radially spaced, circumferentially spaced upwardly inclined side members, the lower ends of which are secured to the shelf, and a rest ring connecting the side members at the tops thereof.
- 55 5. The structure defined in claim 2 which further includes a guard ring above and outward of the rest ring and supported therefrom.
- 60 6. A display rack comprising a plurality of circumferentially spaced upright members, a base ring connecting said members at their lower ends, a plurality of vertically spaced annular shelves within said members, each shelf comprising an outer ring and an inner ring the former of which is rigidly secured

to said members, means connecting the outer and inner rings and holding the same radially spaced, upwardly and inwardly inclined side members rigidly connected at their lower ends to the outer rings adjacent to the upright members, and rest rings connecting the side members at their upper ends.

5. The structure defined in claim 4 which further includes a guard ring supported from the upper rest ring.

6. The structure defined in claim 4 which further includes crossed brace rods, the lower ends of which are secured to the base ring and the upper ends of which are secured to the upper shelf.

7. A display rack comprising a body having an endless lower shelf, and an endless upper shelf, and means above and radially inward of said shelves for holding articles thereon in conical formation, the relative arrangement of said parts being such that bottles or the like in conical arrangement on a lower shelf may project vertically upward beyond the upper shelf with their upper ends radially outward of the axis of the rack, said shelves being formed by approximately concentric wires spaced to hold the articles in radially spaced relation.

In testimony whereof I affix my signature.

EDWARD W. HAMANN.
